FLOOR RACK FOR REFRIGERATOR CARS

Charles E. Crede, Pittsburgh, Pa., assignor, by
mesne assignments, to Standard Railway
Equipment Manufacturing Company, a corpora-
tion of Delaware

Application June 17, 1937, Serial No. 148,629

9 Claims. (Cl. 105—375)

The invention relates to insulated refrigerator cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

The invention relates specifically to "floor racks" for such refrigerator cars which comprise a foraminous or perforated floor, arranged to support the lading in the car in spaced relation to the insulated floor of the car so that air, after it has been cooled by a refrigerant, or heated by a heater, may pass under the lading and through the foraminous floor and up through or between the lading.

The object of the invention is to provide a floor rack for a refrigerator car which is very strong to support vertical loads and has great strength in a horizontal direction (to resist the tendency of a shifting load to move the floor rack sideways) without materially retarding the flow of air below the floor rack or materially reducing the amount of air flow through the floor rack.

A further object is to form a floor rack of a corrugated (or similarly formed) metallic plate to provide a plurality of flues or air channels between the corrugations which communicate with the usual bunker of a refrigerator car, and to support thereon an apertured auxiliary floor having certain parts or zones thereof perforated for air movement therethrough and other parts or zones thereof solid so that air movement through the auxiliary floor may be proportioned to requirements. For instance, in hot weather air leakage around the doorway necessitates more cold air from the refrigerant chamber or bulkhead than is required at the zone near the bulkhead and likewise heat leakage through the side walls of the car may necessitate more cold air from the refrigerant chamber than the zone near the middle of the car.

In the drawings:

Fig. 1 shows the application of my device to a 50 railway refrigerator car.

Fig. 2 is a plan view of my improved floor rack.

Fig. 3 is an elevation of my improved floor rack.

Fig. 4 is a perspective view of my improved floor rack.

55 Figs. 5, 6 and 7 are sections on lines 5—5; 6—6 and 7—7 respectively of Fig. 2.

Fig. 1 shows a typical railway refrigerator car having roof 2, floor 3, end wall 4 and doorway 5.

The bulkhead 6 separates the refrigerant chamber 7 from the lading compartment and is pro-

vided with a grate 8 for supporting ice (for cooling the air) or a stove (for warming the air). The floor rack 10 provides a space 11 between the lading 12 and the floor 3. Air being cooled by the refrigerant descends into the space 11 and rising upwardly through apertures in the floor rack and through or between the lading 12, and being warmed thereby, returns through the opening 13 above the bulkhead to the refrigerant chamber. This air movement is indicated by 10 arrows. When a stove is used for heating the air, of course, the direction of the circulation is reversed. This convection circulation of air is repeated.

In the form of invention illustrated the floor rack rests upon the floor 3 and comprises a metallic plate formed with alternating upper 20 and lower 21 portions connected by preferably diagonal webs 22. The foraminous floor rests upon and is preferably secured to the upper portions 20 of 20 the floor rack. In the form shown the foraminous floor comprises a plurality of spaced apart slats 23 extending normally to the webs 22. The rack is positioned with the webs 22 extending normally to the bulkhead 6, or, as in most cases, 25 parallel to the side walls of the car so that the spaces 25—26 between the webs, that is, both above the lower portion 21 and below the upper portions 20, form a series of parallel air channels which communicate with the refrigerant 30 chamber 7.

Some parts of some of the upper portions 20 are provided with apertures 30 which register with the apertures in the foraminous floor, or as shown, register with the spaces 31 between the 35 slats to allow air movement from the spaces 11 below the upper portions 20 into the lading compartment 8.

Owing to the leakage of heat from the outside to the inside of the car around the doors 5 of 40 the car, it is desirable to provide for more movement of air from the channels to the lading compartment than elsewhere in the car, therefore, I prefer to leave the upper portions 20 imperforate 45 except adjacent said doors, where I provide the apertures 30 in these upper portions.

The zone adjacent the bulkhead 6 is usually the coldest part of the car, therefore, it may be desirable to cover up some of the air channels 25 above the lower portions 21 which, in the form 50 illustrated, is accomplished by providing the plates 35 and 36. These plates may be welded (37) to the upper portions 20. These members or plates extend longitudinally of the car for about one-sixth of the length thereof.

55 The accompanying drawings illustrate the preferred form of the invention, though it is to be understood that the invention is not limited to the exact details of construction shown and described, as it is obvious that various modifications 60

thereof, within the scope of the claims, will occur to persons skilled in the art.

I claim:

1. In a refrigerator car having a lading compartment and a floor, the combination of a rack for supporting a lading in said compartment comprising a plate formed with a plurality of alternating upper and lower portions connected by webs, said lower portions resting upon said floor and said upper portions having secured thereto a foraminous member to form a plurality of flues below the lading and means to induce an air current in said flues, some of said upper portions having apertures only remote from said means which provide communication between certain of said flues and the lading compartment. 5
2. In a refrigerator car having a lading compartment and a floor, the combination of a rack for supporting a lading in said compartment comprising a plate formed with a plurality of alternating upper and lower portions connected by webs, said lower portions resting upon said floor and said upper portions having secured thereto a foraminous member to form a plurality of flues below the lading, means to induce an air current in said flues, some of said upper portions having apertures only remote from said means which provide communication between certain of said flues and the lading compartment and means adjacent said first-mentioned means to enclose a portion of one of the flues disposed above one of said lower portions. 10
3. In a refrigerator car having a lading compartment and a floor, the combination of a rack arranged to support a lading in said compartment and formed to provide a plurality of substantially parallel non-communicative flues and means to induce an air current in said flues, some of said flues communicating with the lading compartment only remote from said means and others of said flues communicating with the lading compartment adjacent said means and also remote from said means whereby the regions of the lading compartment remote from said means may receive a larger quantity of said air than the regions adjacent said means. 15
4. In a refrigerator car having a lading compartment and a floor, the combination of a rack arranged to support a lading in said compartment and formed to provide a plurality of substantially parallel non-communicative flues, and means to induce an air current in said flues, some of said flues communicating with the lading compartment only remote from said means, others of said flues communicating with the lading compartment adjacent said means and also remote from said means and others of said flues communicating with the lading compartment intermediate of the above mentioned adjacent and remote communications whereby the regions of the lading compartment remote from said means may receive a larger quantity of said air than the regions adjacent said means. 20
5. In a refrigerator car having a lading compartment and a floor, the combination of a rack arranged to support a lading in said compartment and formed to provide a plurality of substantially parallel non-communicative flues and means to induce an air current in said flues, some of said flues communicating with the lading compartment over substantially their entire length and others of said flues being enclosed adjacent said means whereby the regions of the lading compartment remote from said means may receive a larger quantity of said air than the regions adjacent said means. 25
6. In a refrigerator car having a lading compartment and a floor, the combination of a rack arranged to support a lading in said compartment and formed to provide a plurality of substantially parallel flues, means to induce an air current in said flues and means providing communication between said flues and the lading compartment of the car, said last-mentioned means having greater area remote from said first-mentioned means than adjacent said first-mentioned means whereby the regions of the lading compartment remote from said first-mentioned means may receive a larger quantity of said air than the regions adjacent said first-mentioned means. 30
7. In a refrigerator car having a lading compartment and a floor, the combination of a rack arranged to support a lading in said compartment and formed to provide a plurality of substantially parallel non-communicative flues and means to induce an air current in said flues, some of said flues communicating with the lading compartment only remote from said means and others of said flues communicating with the lading compartment adjacent said means, the flues communicating remote from said means having a greater total area than the flues communicating adjacent said means, whereby the regions of the lading compartment remote from said means may receive a larger quantity of said air than the regions adjacent said means. 35
8. In a refrigerator car having a lading compartment, a floor, a refrigerant chamber separated from the lading compartment by a bulkhead and a doorway in said wall remote from said bulkhead, a rack arranged to support a lading in said compartment and formed to provide a plurality of non-communicative flues substantially parallel with said wall, said rack and chamber being associated so that a refrigerant in said chamber induces an air current under said bulkhead and in said flues, some of said flues communicating with the lading compartment only adjacent said doorway and others of said flues communicating with the lading compartment adjacent said bulkhead and also adjacent said doorway, whereby the regions of the lading compartment adjacent said doorway may receive a larger quantity of said air than the regions adjacent the means. 40
9. In a refrigerator car having a lading compartment and a floor, the combination of a rack arranged to support a lading in said compartment and formed to provide a plurality of substantially parallel non-communicative flues and means to induce an air current in said flues, some of said flues communicating with the lading compartment only remote from said means and others of said flues communicating with the lading compartment adjacent said means, the area providing communication remote from said means being greater than the area providing communication adjacent said means, whereby the regions of the lading compartment remote from said means may receive a larger quantity of said air than the regions adjacent said means. 45

CHARLES E. CREDE. 70
